[57] ABSTRACT

A suction depanner is provided having an automatic height adjustment means responsive to the height of the product to be depanned. Further, the depanner is provided with self-centering guides for aligning the product.

ARTICLE HANDLING EQUIPMENT

This invention relates to so-called suction depanners for use in bakeries for depanning bread, buns and the like food products.

A suction depanner of the kind to which the invention relates is described in U.S. Pat. No. 3,325,025. The pans or panstraps containing the items to be depanned are fed along a pan conveyor beneath a pickup conveyor which is adapted to individually grip the items by suction and lift them from the pans.

In the depanner described in U.S. Pat. No. 3,325,025 the pickup conveyor can be raised or lowered manually to set the height of the pickup conveyor above the pan conveyor to suit the height of the loaves or other items to be depanned. Also lateral guides (not described in the above-mentioned U.S. specification) are arranged at opposite sides of the pan conveyor for centering the pans beneath the suction conveyor. These guides are manually adjustable to suit the width of the pans. Thus when changing a bakery line over from one size article to another it is necessary to shut down the line for a short while to enable the pickup conveyor and the lateral guides to be adjusted. If these adjustments are forgotten, as may well happen, there is grave danger of the depanner itself being damaged, quite apart from the loss of production and possible damage to the pans.

One feature of the present invention is to provide a suction depanner with automatic height adjustment of the pickup conveyor. This can be achieved by providing a sensor in advance of the pickup conveyor adapted to sense the height of the items in the pans as they approach the pickup conveyor. The sensor can comprise a feeler adapted to operate a hydraulic or pneumatic control valve or electrical contacts or an electrical resistor. Alternatively the sensor can comprise a vertical row of fixed photoelectric devices or two photoelectric devices arranged on the pickup conveyor one above the other. A hydraulic or pneumatic jack or an electrically driven screw jack can be provided for raising and lowering the pickup conveyor responsively to signals received from the sensor.

Another feature of the invention is to provide self-centering guides for the pans on the pan conveyor. These can comprise a pair of pivoted guide arms arranged at opposite sides of the pan conveyor and adapted to swing inwardly towards one another, preferably under spring bias. As the pans are advanced by the pan conveyor they come into engagement with the guide arms and are thereby centered beneath the pickup conveyor. The arms are preferably coupled together mechanically so that they can only swing simultaneously but in opposite directions. The coupling means may comprise a connecting rod linking two cranks provided respectively on the guide arms but out of phase with one another by substantially 180°. Alternatively a twisted belt drive or a gear train can be provided as the coupling means. Advantageously in accordance with a feature of the invention rollers are journaled to the free ends of the guide arms.

The invention is further described, by way of example with reference to the drawings, of which FIGS. 1 to 5 diagrammatically illustrate various parts of a suction depanner constructed generally as described in the above-mentioned U.S. specification but provided with automatic height adjustment in accordance with one embodiment and self-centering guides whereby no ad-

justment of the depanner is required when changing from one size loaf or other item to another size, and of which FIGS. 6 to 9 accompany this Complete Specification and illustrate a second embodiment of automatic height adjustment. In the drawings:

FIG. 1 is a plan view of the self-centering guides,

FIG. 2 is a rear view of the self-centering guides,

FIG. 3 is a detail view of the downstream end of the pickup conveyor,

FIG. 4 is a detail of the support for the pickup conveyor,

FIG. 5 is a detail view of the upstream end of the pickup conveyor in accordance with the first embodiment,

FIG. 6 is a side elevation of the second embodiment,

FIG. 7 is a plan view of the second embodiment,

FIG. 8 is a front elevation of the second embodiment, and

FIG. 9 is a block diagram of the control circuit of the second embodiment.

The first embodiment of suction depanner, parts of which are shown in FIGS. 1 to 5 of the drawings, comprises an endless horizontal conveyor for conveying the pans or panstraps containing loaves, buns or the like items to be depanned. A pickup conveyor is arranged above the pan conveyor at a pickup station. The pickup conveyor comprises an endless belt whose lower run is a generally horizontal portion followed by a gently rising portion. A suction chamber is arranged inside this belt and has an open face which is sealingly engaged by the horizontal and rising portions of the lower run. The conveyor belt is perforated and has attached thereto in registry with the perforations a multiplicity of bellows-like suction cups made of soft rubber. As the belt passes beneath the suction chamber, suction is applied through the perforations to the suction cups. The height of the pickup conveyor above the pan conveyor is adjusted in the manner hereinafter described so that the lower lips of the suction cups engage the tops of the loaves or other items to be depanned. This enables a vacuum to be developed inside the suction cups which due to their bellows-like construction immediately tend to contract to grip the loaves or other items and bodily lift them out of the pans. The rising portion of the lower run of the conveyor belt then lifts the loaves clear of the pans. A discharge conveyor has an inlet end extending beneath the rising portion of the conveyor band so that when the suction cups pass beyond the end of the suction chamber the vacuum is released from the suction cups to deposit the loaves or other items on the discharge conveyor.

All of the above features are more fully described in U.S. Pat. No. 3,325,025 to which reference may be made as necessary to permit a more full understanding of the present invention. Referring now specifically to FIGS. 1 and 2 of the drawings, it is necessary that the pans 20 on the pan conveyor 21 be accurately centered on the pan conveyor 21 as the pans pass beneath the pickup conveyor (not shown in FIGS. 1 and 2.) Such centering is achieved by a pair of guide arms 22 which are attached to vertical spindles 23 journaled in fixed bearings 24. The guide arms 22 are coupled together for simultaneous swinging movement in a horizontal plane by a connecting rod 25. The connecting rod 25 is pivoted to crank pins 26 and 27 attached to discs 28

30

35

40

45

50

55

60

65

and 29 secured respectively to the lower ends of the spindles 23. The crank pins 26 and 27 are 180° out of phase with one another so that the two guide arms 22 are constrained to move simultaneously but in opposite directions, i.e. towards and away from one another and from the longitudinal center line of the pan conveyor 21. A tension spring 30 acts on the connecting rod 25 in a direction to urge the guide arms 22 towards one another. Rollers 31 are journaled to the free ends of the guide arms 22.

As the pans 20 are advanced by the pan conveyor 21 towards the pickup station (which is to the right of that part of the depanner shown in FIG. 1) the pans come into engagement with the guide arms 22. Since these guide arms are constrained to move away from the longitudinal center line by equal amounts they act as a self-centering device to automatically center the pans 20 on the pan conveyor. As the pans proceed between the guide arms the rollers 31 run along the side walls 32 of the pans to hold the pans in a center position. While only one or two pans are shown in the drawings it will be appreciated that in practice the pans follow one another continuously and generally in abutment with one another so that the rollers 31 are substantially continuously running along the side walls 32 thereby holding the arms 22 themselves out of substantial frictional engagement with the pans.

Referring now specifically to FIGS. 3, 4 and 5 of the drawings there is shown therein the pickup conveyor 35 which comprises the endless belt 36 having a plurality of bellows-like suction cups 37 attached thereto. While only one suction cup is shown it will be appreciated that there are hundreds of suction cups attached to the conveyor belt 36. They are arranged in a large number of rows across the central portion of the belt 36, there being about four suction cups in each row and the suction cups in adjacent rows being staggered with respect to one another. The belt 36 has a large number of perforations such that each perforation communicates with the interior of one of the suction cups 37. The lower run 38 of the belt 36 has a generally horizontal or slightly falling portion 39 (FIG. 5) followed by a gently rising portion 40 (FIG. 3). The belt 36 is entrained about rollers 41 and 42 of which the roller 41 is a driving roller driven from an electric motor 43 by means of a belt drive 44.

The rollers 41 and 42 are journaled in a frame 45 on which the motor 43 is mounted. The frame 45 is mounted for vertical movement in a stand 46 the upper end of which is shown in FIG. 3 and the lower end of which is shown in FIG. 4. The stand 46 comprises two uprights only one of which is shown and which are arranged on opposite sides of the pan conveyor (not shown in FIGS. 3 to 5). Two vertical box members 47 form part of the frame 45 and extend downwardly inside the two uprights of the stand 46. These box members are constrained to move vertically and are vertically guided by upper rollers 48 and lower rollers 49 journaled in the stand. Lower ends of the vertical box members 47 are joined by a crosshead 50 which is pivoted to a piston rod 51 of a hydraulic jack 52 arranged beneath the pan conveyor. The crosshead 50 is shown in FIG. 4 in its lowered position and in its raised position as indicated at 50a. The cylinder of the hydraulic jack 52 is pivoted at its lower end to a

bracket 53 at the base of the framework of the depanner.

FIGS. 3 and 5 also show the suction chamber 54 which is provided internally with a number of internal longitudinal ribs which engage the belt 36 to support the belt against the suction in the suction chamber and to define the generally horizontal portion 38 and the gently rising portion 40 of the lower run 38.

A pivot pin 55 of a feeler 56 is journaled in the forward end of a projecting arm 57 on the frame 45 of the pickup conveyor. The loaves or other items are advanced beneath the pickup conveyor in the direction of the arrow 58 and are engaged by the feeler 56 before they reach the suction cups 37. The feeler 56 acts through a spring 59 on an operating rod 60 which is connected to a servo-control valve 61 whose housing is secured to the frame 45. The servo-control valve 61 controls the flow of hydraulic fluid to and from the hydraulic jack 52.

The depanner is provided with a small hydraulic pump which feeds a hydraulic reservoir (both not shown) to maintain a supply of hydraulic fluid for the jack 52. The supply and return lines are connected to the servo-control valve 61 which in turn is connected by two operating lines to the opposite ends of the jack 52. When the servo-control valve 61 is in its central position the hydraulic jack 52 is hydraulically locked in an adjusted position. Clockwise pivoting of the feeler 56 operates the servo-control valve to cause the jack 52 to raise and vice-versa. Thus as the loaves or other items to be depanned are engaged by the feeler 56 the height of the pickup conveyor is rapidly and automatically adjusted by means of the servo-control valve 61 and the hydraulic jack 52 to suit the height of the loaves or other items.

As the loaves or other items proceed beneath the slightly falling portion 39 of the lower run 38 the lower lips 62 of the suction cups 37 are pressed gently into engagement with the top of the loaf or other item and seal to the item. This allows the suction in the suction chamber 54 to draw a vacuum in the suction cup 37 through the corresponding perforation 63. The bellows-like suction cup immediately contracts and lifts the loaf out of the tin. The rising portion 40 of the lower run then lifts the loaf clear of the tin and when the end of the suction chamber 54 is reached the suction in the suction cup is broken to deposit the loaf on a discharge conveyor (not shown).

In practice each item will generally be engaged by several suction cups 37 but not all suction cups will be engaged by an item. This does lead to some loss of vacuum through the associated perforation but not sufficient to impair operation of the pickup conveyor. Since a rather large suction fan is required this fan is mounted beneath the pan conveyor and connected by flexible ducting (not shown) to the suction chamber.

Thus it will be seen that the provision of self-centering guides for the baking tins together with automatic height adjustment of the pickup conveyor provides a suction depanner which does not have to be manually adjusted despite variations and changes in the size of the loaves or other articles to be depanned.

The second embodiment of the suction depanner is shown in FIGS. 6, 7 and 8 of the drawings. It comprises an endless horizontal conveyor 70 which is entrained

about end rollers 71 and 72 journaled in a fixed framework 73. One of the rollers 71 and 72 is driven by means not shown. A pickup conveyor 74 is arranged above the pan conveyor 70 at a pickup station 75. The pickup conveyor 74 comprises an endless perforated belt having attached thereto a multiplicity of bellows-like suction cups made of a soft rubber as described more fully in the previously mentioned U.S. Pat. No. 3,325,025. A suction chamber 76 is arranged inside this belt and has a lower open face which is sealingly engaged by the lowermost portion 77 and a gently rising portion 78 of the lower run of the said perforated belt. A large suction fan 79 is arranged inside the framework 73 and its suction inlet is connected by a flexible conduit 80 to a side extension 81 of the suction chamber 76. The flexible conduit 80 can, for example, be of bellows-like construction. The outlet of the fan 79 discharges through a filter 82. The fan 79 is driven by an electric motor 83.

It is necessary that the bread pans or pan straps (not shown in FIGS. 6 to 8) be accurately centered on the pan conveyor 70. Such centering is effected by a pair of guide arms 84 which are shown in FIG. 7 but omitted from FIG. 6 for clarity. The guide arms are coupled together for simultaneous swinging movement in a horizontal plane in opposite directions. This can be achieved by a connecting rod as described previously with reference to FIGS. 1 and 2 of the drawings or by other suitable means, such as a crossed belt drive or a gear train as previously mentioned. The guide arms 84 are spring biased towards one another like the guide arms 22 and can be provided at their free ends with rollers 85 like the rollers 31.

The endless perforated belt of the pickup conveyor 74 is entrained about rollers 86 and 87 of which the roller 87 is driven by a motor 88. The rollers 86 and 87 are journaled in a frame 89 which also supports the motor 88 and the suction chamber 76. The frame 89 is mounted for vertical movement in a stand 90 which straddles the framework 73 and effectively forms part thereof. This stand comprises uprights 91 and 92 arranged on opposite sides of the pan conveyor 70. Two vertical members 93 and 94 effectively form part of the frame 89 and extend downwardly within the uprights 91 and 92 respectively. These vertical members 93 and 94 are constrained to move vertically and are vertically guided by upper rollers 95 and lower rollers 96. The construction of the vertical members 93 and 94 and the uprights 91 and 92 may be substantially the same as previously described with reference to FIGS. 3 and 4. The lower ends of the vertical member 93 and 94 are joined together by a crosshead 97 which contains a nut of a screw jack 98. The spindle 99 of the screw jack is driven from an electric motor 100 through a suitable reduction gear 101.

A feeler 102 is attached to a spindle 103 which is journaled in a vertically movable side support 104 and extends laterally of the pan conveyor 70 so as to support the feeler 102 generally centrally above the pan conveyor. The spindle 103 is attached to the arm 105 (FIG. 9) of a height measuring electrical transducer in the form of a potentiometer 106. One end of a chain 107, passing around pulleys 108, 109 and 110 which are journaled to the framework 73 is attached to the crosshead 97 and its other end is attached to the verti-

cally slidable column 141 of the side support 104 so that the support 104 is automatically raised and lowered when the pickup conveyor 74 is raised and lowered.

As shown in FIG. 9 the potentiometer 106 and a pre-adjustable reference potentiometer 112 form two branches of a Wheatstone bridge circuit 113 which is connected to a suitable electrical power source shown as a battery 114. The potentiometer arms 105 and 111 are each connected to a positive error signal comparator 115 and a negative signal comparator 116. As more fully described hereinafter, the sensor 102 senses the height of the loaves to be depanned with respect to the height of the pickup conveyor 74 and produces a corresponding signal at the slider arm 105 of the potentiometer 106. If the pickup conveyor 74 is too low the comparator 115 responds and produces a positive error signal which is amplified by an amplifier 117 to energize the solenoid 118 of a forward contactor 119. If the pickup conveyor 74 is too high the comparator 116 responds to the difference between the signals picked up from the potentiometers 106 and 112 and produces a negative error signal which is amplified in an amplifier 120 to energize a solenoid 121 of a reverse contactor 122.

FIG. 9 shows diagrammatically the armature 123 and field winding 124 of the electric motor 100 for the screw jack, this motor being illustrated as a reversible d.c. motor. A battery 125 is shown by way of example as a suitable source of d.c. power for the motor 100. One brush 126 of the armature 123 is connected directly to a negative lead 127 from the power source 125. A positive lead 128 is connectible by a main switch 129 to the positive pole of the power source 125. The positive brush 130 of the armature 123 is connected to an armature lead 131. The forward contactor 119 has a contact arm 132 for connecting the positive lead 128 to a first lead 133 to the field winding 124 and a second contact arm 134 for connecting the armature lead 131 to a second lead 135 from the field winding 124. Thus, when the contactor 119 is energized the motor 100 is driven in a forward direction to raise the pickup conveyor 74. The reverse contactor 122 has a contact arm 136 for connecting the positive lead 128 to the second field winding lead 135 and a contact arm 137 for connecting the armature lead 131 to a resistor 138 which leads to the first field winding lead 133. Thus, when the reverse contactor 122 is energized the motor 100 is driven in a reverse direction to lower the pickup conveyor 74 but at a comparatively slow speed governed by the resistance of the resistor 138. Suitable interlock contacts (not shown) may be provided on the contactors 119 and 122 to prevent both contactors from being operated simultaneously in the event of a fault.

In operation, as with the first embodiment, the pans containing baked loaves of bread or the like product arrive from a cooler at the righthand end (FIGS. 6 and 7) of the pan conveyor 70 and proceed beneath the feeler 102. The feeler 102 rides over the loaves and sets the slider arm 105 of the potentiometer 106 at a position according to the height of the loaves with respect to the height of the support 104. A corresponding potential is thereby delivered to the comparators 115 and 116. Generally, the pickup conveyor 74 will be initially too

low so that the slider arm 105 of the potentiometer 116 delivers a higher potential to the comparators 115 and 116. The positive comparator 115 then responds to the difference between these two potentials and delivers a positive error signal which is amplified by the amplifier 117 and energizes the contactor 119. The motor 100 is thereby connected to the power source 125 (the main switch 129 having previously been closed) and the motor 100 rotates at full speed to raise the pickup conveyor 74. This causes the support 104 to be raised also whereby the slider arm 105 of the potentiometer 106 is moved in a direction to reduce the difference between the potentials from the slider arms 105 and 111 until this difference becomes too small for the comparator 115 to respond. The contactor 119 thereby releases to stop the motor 100 with the pickup conveyor 74 in a vertical position corresponding to the height of the loaves as measured by the feeler 102.

Should the size of the loaves be changed, then the feeler 102 will fall so that the potential on the slider arm 105 of the sensor potentiometer 106 becomes less than the potential of the slider arm 111 of the potentiometer 112. The comparator 116 now responds to the difference between the two potentials, which is now of an opposite sense, and produces a negative error signal amplified by the amplifier 120 to energize the reversing contactor 122. The motor 100 is now caused to rotate in a reverse direction but rotates at a comparatively slow speed due to the presence of the series resistor 138. The pickup conveyor 74 and the support 104 for the feeler 102 are thereby gradually lowered to the new height and stop when the difference between the potentials on the two slider arms 105 and 111 becomes too small for the comparator 116 to respond.

It will be seen that in the absence of any pans being advanced on to the pan conveyor 70 the feeler 102 will adopt its lowermost position illustrated and the pickup conveyor will gradually be lowered to its lowermost position. In practice, when changing over from one size loaf to another there will be a gap between the end of the pans of one size and the beginning of the pans of another size. During this gap the pickup conveyor 74 will be slowly lowered towards its lowermost position and will then be rapidly raised again to the new height when the new sized loaves begin to arrive.

By arranging for the motor 100 to rotate at full speed for raising the pickup conveyor 74 it can be assured that this conveyor has reached the required height before the pans advance beneath the pickup conveyor. By arranging for the motor 100 to rotate comparatively slowly in the reverse direction it can be ensured that when there is a gap between the pans, resulting in release of the feeler 102, the last of the pans arrives beneath the pickup conveyor 74 before it has been lowered a significant distance.

The operation of the pickup conveyor 74 to lift the loaves out of the pans and deposit them on a discharge conveyor is as described with reference to the first embodiment. The position of the discharge conveyor for the depanned products is shown by broken lines 140. One end of this discharge conveyor can be conveniently attached to the uprights 91 and 92. Before the pans move beneath the pickup conveyor 74 they are aligned centrally on the pan conveyor 70 by the guide arms 84 in the manner previously described with reference to the first embodiment.

While the support 104 for the feeler 102 is shown as being vertically movable on the frame 73 it can, if desired, be placed further away from the pickup conveyor 74, e.g. on the outlet end of the cooler, provided that the speed of rotation of the motor 100 is sufficiently slow in the reverse direction.

Naturally, other means and circuitry for operation of the motor 100 are possible. For example, the motor 100 might be a three phase motor which is reversed by reversing the connections to two of the phase winding. The fast and slow speeds could be obtained by gear trains of different ratios selectively brought into operation by means of suitable clutches.

Again, the electronic circuit controlling the motor 100 may be modified by omitting the comparator 116 and the amplifier 120. In this case a single contactor is used which, when energized, operates the motor 100 in the forward direction and when de-energized operates the motor 100 in the reverse direction. In this case the pickup conveyor 74 will be caused to oscillate in height about a mean position but with insufficient amplitude to affect operation of the pickup conveyor.

Whilst a potentiometer has been illustrated as suitable means for measuring the height of the loaves relative to the height of the pickup conveyor 74 other means could be used, such as rows of photo-electric cells. Also, it would be possible to replace the screw jack 98 by a hydraulic jack of the kind described with reference to the first embodiment. In this case the contactors 119 and 122 would be replaced by a suitable solenoid operated changeover valve and the resistor 138 would be replaced by a throttle in one of the hydraulic lines.

Air blast nozzles (not shown) can be arranged above a grid 142 of rods for causing air to blast down between the loaves and the tins to loosen the loaves. The grid 142 restrains the loaves from lifting right out of the pans.

What is claimed is:

1. A section depanner which is provided with means for automatically adjusting the height of the pickup conveyor responsively to the height of the loaves to be removed from the pans including a movable feeler arranged in advance of the pickup conveyor for sensing the height of the product to be depanned, a hydraulic jack for raising and lowering the pickup conveyor, and control means for operating said jack responsively to movement of said feeler.

2. A suction depanner as claimed in claim 1 in which said feeler operates a hydraulic control valve for controlling operation of said jack.

3. A section depanner which is provided with means for automatically adjusting the height of the pickup conveyor responsively to the height of the loaves to be removed from the pans including a movable feeler arranged in advance of the pickup conveyor for sensing the height of the product to be depanned, a jack for raising and lowering the pickup conveyor comprising a screw jack and a reversible electric motor for driving the screw jack, and control means for operating such jack responsively to movement of said feeler.

4. A section depanner which is provided with means for automatically adjusting the height of the pickup conveyor responsively to the height of the loaves to be removed from the pans including a movable feeler arranged in advance of the pickup conveyor for sensing

the height of the product to be depanned, a jack for raising and lowering the pickup conveyor, and control means for operating said jack responsively to movement of said feeler, said feeler being mounted on a forward extension of a support frame for said pickup conveyor and is movable vertically therewith.

5. A suction depanner as claimed in claim 3 in which said feeler operates an electrical transducer for controlling operation of said jack.

6. A suction depanner as claimed in claim 5 in which said feeler is mounted on a fixed frame in advance of said pickup conveyor and in which a feedback transducer is provided for indicating the actual height of said pickup conveyor, said control means including means for comparing the actual height of said pickup conveyor with the height of the product as measured by the feeler.

7. A suction depanner as claimed in claim 6 in which each of said transducers comprises an electric potentiometer with a slider movable respectively by movement of the feeler and by vertical movement of the pickup conveyor.

8. A suction depanner as claimed in claim 7 in which said potentiometers form two branches of a Wheatstone bridge circuit and in which said control means includes an electronic comparator connected between the sliders of said potentiometers and an amplifier for amplifying an error signal produced by the comparator responsively to unbalance of the Wheatstone bridge circuit.

9. A suction depanner as claimed in claim 8 in which

said jack comprises a screw jack and a reversible electric motor for driving said screw jack and including reversing contactor means for the electric motor for the jack, said reversing contactor means being operable by the amplified error signal.

10. A suction depanner as claimed in claim 9 including circuit means for causing said motor to rotate comparatively slowly when in reverse for lowering the pickup conveyor.

11. A suction depanner for removing bread, buns and the like food products from pans including a pan conveyor, a vacuum pickup conveyor located above the pan conveyor for removing the contents from pans moving along the pan conveyor and means for automatically adjusting the clearance between the pan conveying means and the vacuum pickup conveyor to a proper depanning distance as a function of the height of the product in the pans at a location on the pan conveyor upstream relative to the vacuum pickup conveyor.

12. A suction depanner as in claim 11 wherein said means comprises a sensor operable in response to said height and drive means responsive to the output of said sensor for effecting relative movement between the pan conveyor and the vacuum pickup conveyor.

13. A suction depanner as in claim 12 wherein said sensor is mounted upon said pan conveyor.

14. A suction depanner as in claim 12 wherein said sensor is mounted on said vacuum pickup conveyor.
